EYELINER-BRUSH

Irene Kaufman, 400 E. 56th St., Apt. 11E,
New York, N.Y. 10022

Filed Mar. 11, 1969, Ser. No. 16,183

Term of patent 14 years

Int. Cl. D4—02

U.S. Cl. D86—10

FIG. 1

FIG. 2

FIG. 3

FIG. 4

FIG. 1 is a top plan view of an eyeliner brush, showing my new design;

FIG. 2 is a side elevational view thereof;

FIG. 3 is a bottom plan view thereof;

FIG. 4 is an end elevational view thereof.

I claim:

The ornamental design for an eyeliner brush, as shown.
